UNITED STATES PATENT OFFICE.

EDWARD C. POTTS, OF RICHMOND, VIRGINIA.

HAND-STAMP.

1,284,446.

Specification of Letters Patent.

Patented Nov. 12, 1918.

Application filed April 12, 1916. Serial No. 90,622.

To all whom it may concern:

Be it known that I, EDWARD C. POTTS, a citizen of the United States, residing at Richmond, in the county of Henrico and State of Virginia, have invented certain new and useful Improvements in Hand-Stamps; and I do hereby declare the following to be a full, clear, and exact description of the invention, such as will enable others skilled in the art to which it appertains to make and use the same.

This invention relates to improvements in hand stamps, and has for its primary object to provide an improved handle movably or flexibly connected with the plate carrying the printing surface, thereby insuring a full and uniform impression of the latter upon the sheet of paper or other article to be printed.

With this and other objects in view, the invention consists in the novel construction, combination and arrangement of parts as will be hereinafter specifically described, claimed and illustrated in the accompanying drawing, in which:

Figure 1 represents a longitudinal sectional view through the improved hand stamp,

Fig. 2 represents an enlarged transverse sectional view therethrough,

Fig. 3 represents a longitudinal sectional view through a modified type of the hand stamp,

Fig. 4 represents a transverse sectional view through the type of hand stamp illustrated in Fig. 3,

Fig. 5 represents a sectional view through a further modified type of the hand stamp,

Fig. 6 represents a perspective view of the spring washer embodied in the modification illustrated in Fig. 5 removed.

Referring to the drawing in detail, where-in similar reference numerals designate corresponding parts throughout the several views, the numeral 5 indicates a holder plate for supporting the rubber stamp or printing surface 6, and which is preferably constructed of sheet metal and has secured to the upper end thereof a substantially rectangular casing 7. The top of the casing is formed with a central aperture 8 loosely receiving a shank 9 carried by a handle 10. The end of the shank 9 opposite the handle 10 is formed with a head having a semi-spherical outer end 11 and a convex inner

surface 12 curved eccentrically with relation to the semispherical part 11. A washer 13 is loosely mounted upon the shank 9 and engages on one side with the convex surface 12 of the head and upon the opposite side 60 with the medial portion of a curved leaf spring 14, the ends of which are engaged with the casing 7 and tend to normally retain the head 11 in firm engagement with a seat or concavity 15 formed centrally in the 65 plate 5.

The tension of the spring 14 operating against the washer 13 and head 11 normally retains the shank 9 and handle 10 in a position at right angles to the holder plate 5. 70 The handle, however, may be moved out of its normal position with relation to the plate 5 and when so moved the cam or convex surface 12 of the head operating against the washer 13 compresses the spring 14 and thus 75 when the handle 10 is released the tension of the spring automatically returns the handle to normal position.

Referring in detail to the modification of the invention illustrated in Figs. 3 and 4 80 the numeral 16 indicates a stamp supporting plate in which is anchored a bearing member 17, having a flanged upper end 18 positioned through and securing the medial portion of a curved spring 19, having the free ends directed away from the plate 16. A second spring 20 curved oppositely to the spring 19 is connected at its ends with the spring 19, as indicated at 21, and the central portion is apertured to loosely receive a shank 22 85 carried by a handle 23. The outward movement of the spring 20 with relation to the holder plate 16 is limited by a pair of flanges 24 embracing the medial portion of the spring 20 and having inwardly directed upper terminals 25.

One end of the shank 22 is formed with a head having a semispherical portion 26 movably engaged in a seat or concavity 27 formed in the bearing member 17 and a convex surface 28 disposed eccentrically with relation to the semispherical portion 26 to provide a cam surface which engages a washer plate 29 loosely fitted upon the shank 22 and engaged with the inner or lower surface of the spring 20. 100

In this type of the hand stamp, the handle 23 is normally retained in a predetermined angular position with relation to the plate 16 by the tension of the two springs 110

19 and 20, one of which engages the washer 29 and acts upon the cam convex surface 28 of the head.

Referring to the modification illustrated 5 in Figs. 5 and 6, the numeral 30 indicates a holder plate in which is anchored a bearing member 31, having a flange 32 at one end under which is anchored the lower flanged 10 edge of a substantially rectangular casing 33. The central portion of the upper wall of the casing 33 is formed with an aperture loosely receiving a shank 34 carried by a handle 35, the shank being provided at one 15 end with a head having a semispherical portion 36 movably mounted in a seat or concavity 37 formed in the adjacent end of the bearing member 31. The inner surface 38 of the head is convex and curved eccentrically with relation to the semispherical portion 36 and engaged with a washer 39 loosely 20 mounted upon the shank 34 and arranged within the casing 33. A spring washer plate 40 is mounted upon the shank 34 between the washer 39 and the top of the casing 33 and is provided with a plurality of 25 radially projecting spring arms 41, some of which are directed angularly and engaged

with the front wall of the casing 33 and others being directed in the opposite direction and engaged with the washer plate 39 for 30 normally retaining the shank 34 and handle 35 in a predetermined angular position with relation to the plate 30.

What I claim is:

A hand stamp including a holder plate, 35 a substantially rectangular casing secured to the upper side of said plate, said plate provided with a central aperture, a handle, a shank at one end of the handle extending through the casing, a head formed on the 40 free end of the shank and having a convex inner surface curved eccentrically with relation thereto, a curved leaf spring arranged within the casing and engaging said head to normally retain the head in firm engagement 45 with the holder plate, as and for the purpose specified.

In testimony whereof I affix my signature in presence of two witnesses.

EDWARD C. POTTS.
